United States Patent Office

Des. 195,738
Patented July 23, 1963

195,738

BOTTLE

William P. Grasty, Zion, Ill., assignor to Abbott Laboratories, North Chicago, Ill., a corporation of Illinois

Filed Nov. 26, 1962, Ser. No. 72,597

Term of patent 14 years

(Cl. D58—6)

FIG. 1

FIG. 2

FIG. 3

FIG. 4

FIG. 5

FIG. 6

The dominant features of the design reside in the portions shown by full lines.

I claim:

The ornamental design for a bottle, substantially as shown and described.
